Patented Nov. 8, 1921.

ROBT. E. CARMICHAEL, INVENTOR

Jesse R. Stone ATTORNEY

UNITED STATES PATENT OFFICE.

ROBERT E. CARMICHAEL, OF HOUSTON, TEXAS.

PUMP-PLUNGER.

1,396,714.

Specification of Letters Patent. Patented Nov. 8, 1921.

Application filed July 15, 1920. Serial No. 396,517.

To all whom it may concern:

Be it known that I, ROBERT E. CARMICHAEL, a citizen of the United States, residing at Houston, Texas, have invented a certain new and useful Improvement in Pump-Plungers, of which the following is a full, clear, and exact description, such as well enable others skilled in the art to which it appertains to make and use the same.

10 My invention relates to an improvement in pump plungers, and has particular application to pumps for use in deep wells in handling oil or water when the same are mixed with quantities of sand or grit tending to wear the plunger.

An object of my invention is to provide a plunger having automatically expanding means thereon which will, by expanding, take up the wear caused by working of the 20 pump, and hence maintain a tight contact between the plunger and working barrel for long periods of time.

Another object is to provide a plunger which will be automatically adaptable to 25 take up wear and which will also be simple in structure, easy to repair and economical to manufacture.

Referring to the drawing forming a part 30 of this specification, and wherein like numerals of reference are applied to like parts throughout the several views; Figure 1 is a central longitudinal section through a pump barrel and my improved plunger therein. Fig. 2 is a central longitudinal section through my improved expanding cup, and Fig. 3 is a top plan view thereof.

I have shown my expanding means as used 40 upon a plunger of ordinary construction attached at the lower end of a hollow pump rod 1, and working within a pump barrel 2. The body of the plunger comprises a central tubular member 3 attached by means of a coupling 4 to the pump rod 1. At the 45 point of connection between the pump rod and the plunger 3, I have attached a valve seat 5 of ordinary construction, within which an upwardly opening ball valve 6 is seated.

My expanding means comprises a cup 7 50 slidably mounted upon the outer face of the plunger 3. This expanding cup is preferably made up of some tough flexible material, such as hard rubber, Babbitt metal, or some composition which may be moved outwardly against the wall of the working bar-

rel. The cup is somewhat frusto-conical in shape, having the larger end placed upwardly upon the plunger and having the upper face beveled inwardly at 8 to a point closely adjacent the plunger, where it is 60 beveled inwardly at a sharp angle. The inner face of the cup is cylindrical in shape and has a kerf or groove 9 cut therein for a distance of approximately half way through the material at that point. The said kerf allows 65 the upper part of the cup to bend outwardly, the kerf opening up as the movement outwardly proceeds. By this provision non-resilient materials, such as lead, may be used in making the cup. The cup is 70 also divided longitudinally into a plurality of parts. In Fig. 3 I have shown the cup as thus divided into four sections, the division line 10 of these sections being cut approximately tangent to the inner face of the cup. This, as will be noted, will allow an 75 outward expansion of the longitudinal sections of the cup and will maintain a tight contact between the sections.

In securing this cup in position upon the 80 plunger I use a cup shaped washer 11, of such size and shape as to closely fit about the lower end of the cup 7 and to extend upwardly on the outer surface thereof to a point somewhat above the inner kerf 9. The 85 cup and the washer are secured upon the plunger by means of locking nuts 12 and 13 threaded upon the lower end of the part 3.

Above the cup 7 I provide a slidable conical collar 14. The smaller end of this collar 90 is pointed downward and is adapted to fit within the beveled upper face of the cup 7. This collar 14 serves as an expanding member and is adapted when forced downwardly within the beveled upper end of the cup 7 95 to force the sections thereof outwardly into contact with the working barrel.

The means by which the collar 14 is forced 100 downwardly comprises a spiral spring 15 surrounding the tubular plunger 3, and bearing at its upper end upon a nut 16 threaded upon the outer face of the plunger below the coupling member 4. The spring 15 bears at its lower end upon a washer 17 seated upon the upper face of the collar 14. The 105 washer 17 is threaded on its outer face for attachment to a tubular housing 18, which extends upwardly about the spring and the coupling 4 and has an inwardly projecting flange 19 at its upper end fitting closely 110

about the pump rod 1. A slidable but fluid tight fit is maintained between the housing and the pump rod 1, by means of a stuffing box 20 of ordinary construction.

5 The operation of my device will now be apparent. When the plunger is reciprocating within the working barrel the upper outer point 21 upon the cup 7 will bear tightly against the inner face of the working barrel and thereby maintain the necessary suction to cause the customary operation of the plunger. Sand and grit which may be carried in suspension within the liquid being pumped will be scraped away from the 10 face of the working barrel and will not be allowed passage upwardly outside the cup. Wear will be caused, however, upon the edge 21 and the spring 15 will serve to force the collar downwardly, and thus act to exert 15 a constant pressure outwardly against the cup 7 causing it to automatically expand during operation and take up any wear which may occur. As the cup 7 is gradually expanded it will cause the upper end thereof 20 to be forced outwardly opening the cup at the kerf 9, the lower portion of the cup not expanding. This will continue until the upper portion of the cup has been worn away 25 sufficiently, and when this point has been 30 reached a new cup 7 may be supplied.

The housing 18 will serve to prevent fluid and sand from coming in contact with the spring 15, and will thus assure the constant and accurate working of the expanding 35 means. As will be obvious, my expanding cup may be cheaply made and will wear for long periods before it is necessary to renew the cup, and when a renewal is necessary the cup may be quickly removed and replaced without the loss of time and expense.

Having thus described my invention, what I claim as new and desire to protect by Letters Patent is:

1. In a pump plunger, an expanding cup 45 comprising a frusto-conical tubular member longitudinally divided on planes tangent to the inner face thereof, a cup-shaped washer to retain said sections together, a recessed upper face on said cup, a conical 50 expanding member fitting therein, and resilient means bearing on said expanding member to automatically expand said cup during the operation of the plunger.

2. In a pump plunger a tubular member, 55 an expanding cup thereon comprising a frusto-conical member slidable upon said

tubular member, a cup shaped washer fitting about the lower portion of said cup, said cup having an annular kerf on the inner face thereof, and means to force said expanding 60 cup outwardly in the manner described.

3. In a pump plunger a tubular member, a cup shaped washer thereon, an expanding cup fitting within said washer and having an inner kerf below the upper end of said washer, 65 said cup being longitudinally divided into a plurality of parts on planes tangent with the inner face thereof, a conical expanding member fitting within the upper end of said cup and resilient means forcing said expanding 70 means into contact with said cup.

4. In a pump plunger a tubular member, a cup shaped washer thereon, a frusto-conical expanding cup seated in said washer, said cup being divided longitudinally into 75 a plurality of sections, a beveled recess on the upper face of said cup, a sharp outer edge on said upper face, an expanding means fitting within said recess, a spring bearing upon said expanding means and adapted to force the same downwardly in 80 the manner described, and means to protect said spring from sand.

5. In a pump plunger a tubular member, an expanding cup secured thereon, an expanding means bearing against the upper 85 face of said cup, a spring bearing against said expanding means and tending to force the same downwardly against said cup, and a housing for said spring slidable upon said 90 plunger.

6. In a pump plunger a tubular member, a longitudinally divided cup thereon, means to expand one end of said cup independently of the other, means to retain the non-expanding end in position, all that part of said cup above said retaining means being adapted to expand simultaneously.

7. In a pump plunger, a frusto-conical shaped cup longitudinally divided along 100 planes tangent to the inner face thereof, a cup shaped washer fitting over the smaller end thereof, an annular kerf cut on the said inner face adjacent the upper end of said washer and means to force the larger end of 105 said cup outwardly in the manner described.

In testimony whereof, I hereunto affix my signature this the 10th day of July, A. D. 1920.

ROBERT E. CARMICHAEL.
